UNITED STATES PATENT OFFICE.

RALPH W. HURD, OF MASON CITY, IOWA.

EGG-CASE.

SPECIFICATION forming part of Letters Patent No. 732,413, dated June 30, 1903.

Application filed November 1, 1902. Serial No. 129,718. (No model.)

To all whom it may concern:

Be it known that I, RALPH W. HURD, a citizen of the United States, residing at Mason City, in the county of Cerro Gordo and State 5 of Iowa, have invented a new and useful Egg-Case, of which the following is a specification.

My device consists of an improved packing and candling device for eggs, whereby the eggs may be more conveniently and rapidly handled than by the old system of crating the eggs in layers, necessitating the removal and examination of the eggs one at a time. In 10 my device one dozen eggs may be candled at a time without removing the eggs from their 15 package.

Another object of my invention is also to provide a strong durable package that will not take up more room than the present usual mode of packing and will permit the usual 20 number of eggs to be shipped in a crate.

My device is fully illustrated in the accompanying drawings, in which—

Figure 1 is a perspective view of my device. Fig. 2 is a similar view with the inner case 25 or drawer partly withdrawn. Fig. 3 is a plan view of the inner section. Fig. 4 is a section on or about the line 4-4 of Fig. 1. Fig. 5 is a detail view of one of the divisional strips.

In carrying out my invention I employ two 30 cases A, open at both ends and secured together by glue, cement, or other suitable means. The cases are oval in cross-section, their vertical diameter being the longer after the cases are secured together. Along one 35 side and adjacent the top of the cases are produced six rectangular openings. (Shown at A'.) Upon the other side of the casing and diametrically opposite are a similar number of like openings A², Fig. 4. As shown in Fig. 40 1, the upper series of openings are both produced on the forward side of the cases and the lower series (not seen in this figure) are upon the rear side. It is obvious that by holding the cases so as to bring the rear openings 45 into the same plane as the front opening with which they register the user can look through all the openings at practically the same time.

The drawer or inner case B is a half-section of a similar case sufficiently reduced in diameter to slide readily into and out of the

case A, as clearly shown in Fig. 2. This inner section has produced in it a series of openings B', which are adapted to register with the openings A². The walls of this inner section are not of a sufficient height to obstruct the upper series of openings in the cases A. The two inner half-sections are connected together at one end by a strip B², there being a sufficient space between the inner walls of the two sections to receive the inner walls of the two outer cases, as clearly shown at B³ in Fig. 3.

Between each of the openings B' is secured an upright oval divisional strip C, the strips 65 having lugs C' projecting from their sides at right angles to the body of the strip and by which they may be secured, preferably by glue or cement, to the bottom and walls of the half-section B. These divisional strips 70 not only serve as partitions, but also act as braces for the outer case, while the two end strips serve to close both ends of the cases when the inner sections are in position.

From the description and drawings it is obvious that, the cases being of suitable size, 75 an egg will be securely held in each of the divisions into which the cases are divided; that by withdrawing the inner sections all the eggs can be at once removed from the 80 cases, and, furthermore, that, as the openings in the inner sections register with the openings in the rear of the outer sections and that these last in turn are adapted to register with the openings in the upper forward part of the 85 outer case, by holding the device up to a light all the eggs contained therein can be candled without opening the package or removing the eggs therefrom. It is also obvious that where each package carries twelve inner compartments one or more dozen eggs can be quickly 90 and conveniently removed from the crate by lifting out the required number of packages, the term "package" as used herein being applied to the complete device, as shown in 95 Fig. 1.

It is of course evident that any number of openings can be produced in the walls of the cases and any number of divisional strips used; but a package adapted to hold twelve 100 eggs is most convenient. It is also obvious that by changing the size of the cases my

packages can be used for the transportation of fancy fruit, and when used for this purpose the openings will permit inspection of each piece of fruit without having to handle the fruit itself.

Having thus fully described my invention, what I claim as new, and desire to secure by Letters Patent, is—

1. In a device of the kind described, the combination of a casing oval in cross-section and having a series of openings produced along its side adjacent the top, a series of openings diametrically opposite the first-mentioned series, a similar casing secured to one side of the first-described casing, inner half-sections secured together by a cross-piece at one end, adapted to slide in the casings, respectively, and divisional strips carried by the half-sections adapted to divide the outer cases into separate compartments, said half-sections having a plurality of openings produced

in their walls adapted to register with the openings in the outer cases.

2. In a device of the kind described, a package comprising two cases open at the ends, said cases being rigidly secured together side by side and each case having two series of openings produced therein, one series being adapted to register with the other, half-sections secured together and adapted to slide into the cases, respectively, said sections having a series of openings adapted to register with the openings in the case in which the section slides, and divisional strips secured to the half-sections and adapted to divide each side of the package into a plurality of compartments.

RALPH W. HURD.
